FLOATING ROOF TANK AND PIPING
THEREFOR

Wilbur G. Laird, Pleasantville, N. Y.

Application June 15, 1944, Serial No. 540,503

6 Claims. (Cl. 220—26)

1

This invention relates to improvements in floating roof storage apparatus for liquids, and more particularly to improvements in pipe connections for supplying liquid to and withdrawing liquid from such tanks, for draining floating roofs and for supplying or removing gases and vapors to and from floating roof tanks.

In general, the improvements are particularly applicable to storage tanks of relatively large diameter used for storing volatile liquids such as 10 crude oil and gasoline.

Floating roof storage tanks for liquids have been provided with swing lines of various types for supplying and removing liquids; with collapsible or folding drainage lines for removing rain water from floating roofs; and with folding lines for other purposes such as for supplying fire extinguishing fluid to tanks provided with floating roofs. Various proposals have been made for constructing zig-zag roof drainage lines and swing lines to prevent their normal thrust action on the floating roof, but so far as known, such proposed structures have not proved entirely satisfactory. Swing lines and drainage lines connected to floating roofs are known to cause considerable trouble because of their thrust action, and because they shift or rotate the roof in the tank.

Having in mind the difficulties normally encountered in the use of swing lines and drainage lines in floating roof storage tanks for liquids, the primary object of the present invention is to provide a floating roof storage tank having the necessary pipe connections which actually are mounted in such a way as to prevent thrust action in connection with the floating roof and prevent rotation of the roof in the tank.

Accordingly, the improved floating roof liquid storage apparatus and improved pipe connections therefor comprise in general a storage tank or container with a floating roof therein, a swivel jointed pipe line in said tank having one end opening thereto, said line comprising a plurality, preferably an even number of rigid pipe sections interconnected in zig-zag manner by swivel joints and connected to a fixed line leading from the tank by a swivel joint, and means connected with each of the pipe sections, preferably at the midpoints thereof, and adapted to control or restrict the folding and unfolding action of said pipe line. The means referred to is adapted to cause the open end of the zig-zag line to move in a substantially vertical straight line so that when the open end of the line is attached to the floating roof the point of attachment is restricted to such vertical line movement.

2

The improvements of the present invention, as will be apparent by the following more detailed description, have many advantages, among which are:

- 5 1. Complete elimination of floating roof thrust usually caused by swing lines and drainage lines.
2. Prevents instability of the floating roof.
3. Controlled and predetermined movement of zig-zag folding line sections.
4. Avoidance of roof thrust due to sticking of swivel joints.

Other advantages derivable from the improvements in liquid storage apparatus of the present invention will be apparent to those skilled in the art from the following description thereof taken in connection with certain illustrative examples shown in the accompanying drawings.

In the drawings:

Fig. 1 is a vertical sectional view of a cylindrical floating roof liquid storage tank showing one form of the invention.

Fig. 2 is a view similar to that of Fig. 1 showing a modified form of the invention.

Fig. 3 is a broken vertical sectional view of a portion of a tank provided with a floating roof showing a modification of a portion of the structure illustrated in Fig. 1.

Fig. 4 is an enlarged view of a folding jointed swing line like that shown in Fig. 3 with a modified form of floating roof attachment.

Fig. 5 is a broken sectional view of the structure shown in Fig. 4 taken at right angles.

Referring to the drawings, the features of the invention are illustrated in connection with an ordinary cylindrical tank provided with a floating roof. In Fig. 1 the tank comprises a shell or side wall 10 and a bottom plate 12, while the floating roof includes a crowned or cone-shaped roof-plate 14 and a marginal flange or apron 16 secured in fluid-tight manner to the roof plate. The tank is provided with a swing line for supplying liquid to and removing liquid from the tank which includes a plurality of relatively long rigid pipe sections 18 and 20 secured together and to a pipe line leading from the bottom of the tank by means of suitable swivel joints 22. The upper open end of the swing line and other movable parts of the line itself may be raised and lowered with respect to the floating roof by means of a cable attached to the end of pipe 20 by means of a device as shown and winch means 24 mounted in an elevated housing 26 in the far side of the roof near the tank wall.

The swing line mechanism may include two or more swivel-jointed pipe sections preferably

an even number and preferably of equal length, and also includes a control mechanism adapted to cause the upper end of the swing line to move vertically in a straight line as the pipe line folds or unfolds. This control mechanism comprises a series of interconnected rigid links, which in the example shown, includes a short rigid link 28 fastened at one end by a pivot joint to the midpoint of the pipe 20 and at the other end to one end of a long link 30, the midpoint of which is secured by a pivot connection to the middle of the pipe section 18. The lower end of the link 30 is provided with a wheel or roller 32 which is permitted to move only in a straight-line horizontal path by a long retaining bracket 34 fixed to the bottom 12 of the tank.

In the example as shown, the length of the rigid link 30 which may be made of any suitable material is the same as that of the pipe sections 18 and 20, while the link 28 is one half the length of the link 30. These relationships are understood to be based upon the lengths between pivot points of the pipe sections and links, the axis of roller 32 being a pivot point. It will be apparent from a consideration of the relationships created by the pipe and link arrangement as shown that when the swing line either folds or unfolds, the upper open end (at the point of cable attachment) must follow a straight-line vertical path. This action not only avoids a thrust on the floating roof, but actually tends to prevent effective thrust from other causes, and also tends to keep the roof from rotating.

While the link 30 and the pipe sections 18 and 20 are illustrated and described as being of the same length from pivot to pivot (link 28 being one half), and provide a very practical and compact arrangement (which also provides for vertical movement of the sheave 78 of Fig. 3), it is not necessary that all links and pipe sections have these relationships. So long as the links and pipe sections together form a parallelogram they will yield the desired result. Vertical movement is also obtained if in the four-sided figure formed by the link and pipe sections, the link portions are equal and the pipe portions are equal, even though the length of the link portions is different from that of the pipe portions in the figure. Other length relationships of links and pipe sections may be compensated for, by providing a suitably formed retaining bracket and track for the roller 32, where its path is not horizontal, so that vertical movement at the desired point is obtained. These modifications and relationships apply to all forms of the invention.

Since the floating roof of the tank shown in Fig. 1 is open to the atmosphere, it is necessary to provide a drain line. In this instance the drain line is constructed, and functions in exactly the same manner as the swing line described above, except that it is fixed to and connected through the edge of the crowned roof plate 14. As shown, the drainage line for the roof comprises a plurality of rigid pipe sections 36 and 38 connected by fluid tight swivel joints to an outlet line 40 and to a fixed pipe connection 42, secured to and opening through the roof plate 14. The pipe sections 36 and 38 are also interconnected by a fluid tight swivel joint the same as pipe sections 18 and 20. The drainage line mechanism also includes links 44 and 46 preferably mounted in exactly the same manner with the same relationships as the links 28 and 30, although the other relationships referred to may

be used. The drainage line with its connecting links 44 and 46 folds and unfolds in the same manner as the swing line, and causes the pipe connection 42, and the portion of the floating roof connected thereto, to move in a straight path vertically as the liquid level in the tank changes.

In the floating roof tank as shown in Fig. 1, the swing line mechanism and the drainage line mechanism are mounted at the 90° points to each other and near the edge of the roof so that together they not only do not cause thrust action on the floating roof, but actually tend to stabilize the floating roof and prevent rotation. If desired, drainage lines of the type shown may be placed on opposite sides of the floating roof or at any other point or points, depending upon the drainage characteristics of the particular roof to be drained.

The tank shown in Fig. 2 is a similar to that shown in Fig. 1 and comprises a shell 48 and a bottom plate 50. In this instance, the floating roof comprises a roof plate 52 surrounded by an apron 54 secured to the plate in fluid-tight manner and which extends above and below the plate. The downward extending portion of the apron 54 is adapted to seal in the liquid and to trap gas below the roof plate 52, which may be removed through a dome 56. The gas collected under the plate 52 may be removed from the dome 56 by means of a gas line comprising a plurality of rigid pipe sections 58 and 60 of equal length and which are connected together, and to an outlet connection from the dome 56 by means of swivel joints. The pipe section 60 is also connected by a swivel joint with a pipe line at the top of the tank which is fixed thereto by means of a bracket 62.

The operation of the gas discharge line including the sections 58 and 60 is controlled by means of a rigid link mechanism such as that described above in connection with Fig. 1. The links comprise an upper short link 64 and a long link 66, the lower end of which is provided with a wheel or roller adapted to move back and forth in a horizontal bracket frame 68. The bracket 68 and the interconnected links 64 and 66, together with the pipe sections 58 and 60 restrict the folding and unfolding action of the gas line so that the point of connection to the dome 56 must move in a straight-line vertical path.

The gas line mechanism shown in Fig. 2 is preferably mounted close to the edge of the floating roof, and the roof is preferably provided with a drainage apparatus identical with that shown in Fig. 1. The gas line comprising pipe sections 58 and 60 may if desired be used for supplying liquid to the tank or for supplying gas thereto. The gas may be supplied from any source and for any desired purpose as for example from a gasoline tank having a fixed roof. In fact, the floating roof shown in Fig. 2 may be provided with a relatively long downwardly extending apron which seals in the liquid in the tank, so as to provide for a relatively large maximum gas capacity above the liquid level in the tank.

Fig. 3 shows a modified form of the swing line mechanism shown in Fig. 1 in which means is provided for operating the swing line from the outside of the tank instead of from the floating roof. This means is illustrated as comprising an outside winch 70, and a cable 72 which passes over a sheave 74 mounted on the rim of the tank wall. The cable 72 also passes through a liquid sealing tube 76 in a dome near the edge of the floating roof, then around a sheave 78 mounted at the

pivot of the links 28 and 30, from which it extends to a lug 30 under the dome.

From the relationship of the pipe sections 18 and 20, and the links 28 and 30 in Fig. 3 (which are the same as in Fig. 1), it will be apparent that as the floating roof moves up and down in the tank, the upper end of the pipe section will remain in exactly the same relative position. In this form of the apparatus, the swing line is not rigidly fixed to the floating roof but the vertical straight line motion tends to keep the floating roof from rotating and from shifting in the tank. The weight of the swing line mechanism is supported by the cable 72 around the sheave 78 and will also tend to prevent any thrust action or rotation of the floating roof. The portion of the cable 72 outside the tank or the winch mechanism may be employed to indicate the position of the swing line in relation to the roof.

Figs. 4 and 5 illustrate a method of attaching the upper end of a swing line to a floating deck whereby the open end of the swing line may be adjusted vertically in relation to the floating roof while thrust is eliminated and the floating roof is prevented from rotating. The apparatus shown in Figs. 4 and 5 comprises a swing line composed of a plurality (preferably an even number) of rigid pipe sections 82 and 84 connected together and to a line 86 leading from the tank through wall 81. Line 86 may be fastened to the bottom of the tank 88 by means of a clamp as shown. As in Fig. 1, the swing line in Figs. 4 and 5 includes a link mechanism 90 which is mounted and which operates in exactly the same manner as that shown in Fig. 1. The upper end of the pipe 82 is provided with a pair of flanged side wheels 92 which are movable up and down between vertical members 94 comprising a part of a frame work erected under a dome 96 in the floating roof 98. The upper end of the pipe 82 may be moved up and down with respect to the floating roof by means of a threaded shaft member 100 which passes through a corresponding threaded member attached to the axle of one of the wheels 92. The threaded member 100 is provided with a hand wheel above the dome 96.

By operating the hand wheel on the member 100, an operator may set the outlet of the swing line shown in Figs. 4 and 5 at any desired point either below or above the liquid level in the tank. With this mechanism furthermore, the swing line apparatus, including the link means 90, prevents lateral movement of the dome 96 as the floating roof moves up and down in the tank with changes in the tank contents. The mechanism therefore has the function of preventing any thrust action by the swing line, and at the same time prevents rotation of the roof (the swing line preferably being mounted near the side of the tank).

It is to be understood that in zig-zag folding piping in which more than two pipe sections are employed (an even number being preferred), each section will be pivoted at an intermediate point to a link member. For example a four section line would have three long links and a short one. The pivot or swivel joints are preferably adapted to permit only up and down motion of pipe sections and links, although other motion may be provided for if desired.

The swing lines shown in Figs. 1, 3, 4 and 5 may be used for the removal or supply of gas to or from under a floating roof of the type shown in Fig. 2, as well as for the removal and supply of liquid. Under normal conditions, the swing

lines shown in Figs. 1, 3, 4, and 5 will be held up under the floating roof, so that their outlets will be above the liquid level.

In erecting a drainage line such as that comprising the pipe sections 36 and 38, the links 44 and 46, together with the roller attached to the link 46 may be reversed, so that the roller operates in substantially horizontal position under the floating roof instead of operating along the bottom of the tank.

From the foregoing description of the various forms of the invention, it will be apparent that the applicant has provided advantageous zig-zag folding piping arrangements for liquid storage tanks which are particularly adapted for use in connection with floating roofs. It will be furthermore apparent that various modifications may be made such as the use of one or more of the lines for supplying fire extinguishing fluids, or for other purposes. Such modifications are contemplated within the spirit and scope of the present invention, as shown by the appended claims.

Having described the invention in its preferred form, what is claimed as new is:

1. In a liquid storage apparatus including a tank, an improved piping arrangement therefor comprising a vertically-foldable zig-zag swivel-jointed pipe line vertically mounted in said tank, said line comprising an even number of rigid pipe sections of substantially equal length interconnected by swivel joints and connected to a fixed outlet pipe from said tank by a swivel joint, a plurality of interconnected rigid links pivotally connected end to end and to the midpoints of each pipe section, a terminal link of said plurality of links pivoted at its mid-point to the pipe section connected to the outlet pipe and having a free end held in horizontal straight line sliding engagement with a portion of said tank near said fixed outlet pipe, the other terminal link being about one half the length of a pipe section and having one end pivoted to a pipe section, said links being connected with each other and with said pipe sections in a parallelogram arranged so as to control the folding and unfolding action of said sections.

2. A liquid storage apparatus comprising a tank and a floating roof therein, two swivel-jointed zig-zag pipe lines each vertically mounted in said tank at right angles to each other and each having one end opening thereinto, and attached to the roof, each of said lines comprising an even number of rigid pipe sections interconnected by swivel joints and connected to a fixed pipe line leading from the tank by a swivel joint, and means connected with each of the pipe sections of each pipe line and adapted to control the folding and unfolding action of said lines so that the open end of each pipe line is caused to move in a substantially vertical straight line said means for each line including a rigid link for each pipe section, the links being connected end to end with pivot joints, one terminal link being one half the length of the other links and having an end pivoted to one terminal pipe section at its midpoint while the remaining links are respectively pivoted at their mid-points to the mid-point of corresponding pipe sections, the free end of the other terminal link being mounted in restricted horizontal sliding engagement with the container.

3. A drainage apparatus for a movable roof for a container, comprising a down drain line having its upper end connected to the roof by a swivel joint and its lower end connected to a fixed outlet

line at the bottom of the container by a swivel joint, said drain line including an even number of rigid pipe sections of substantially the same length connected together by one or more swivel joints, and means connected with said pipe sections and with the bottom of the tank adapted in conjunction with said swivel jointed pipe sections to restrict the vertical movement of said roof, at the point of attachment of said drain line, to a straight-line substantially vertical motion said means including a rigid link for each pipe section, the links being connected end to end with pivot joints, one terminal link being one half the length of the other links and having an end pivoted to one terminal pipe section at its mid-point while the remaining links are respectively pivoted at their mid-points to the mid-points of corresponding pipe sections, the free end of the other terminal link being mounted in restricted horizontal sliding engagement with the container.

4. In a liquid storage apparatus comprising a tank member and a floating roof member therein, a swivel jointed foldable pipe line mounted in said tank having one end opening thereinto and attached to said roof member, said line comprising an even number of rigid pipe sections of approximately equal length interconnected by swivel joints and connected to the tank member by a swivel joint, and means including a series of rigid links connected end to end by pivot joints, a link of said series being connected with each of said pipe sections at substantially their midpoints, and a terminal link of said series having an end mounted in sliding straight line engagement with one of said members, said links being connected with each other and with said pipe sections in such a manner as to form a parallelogram involving the swivel joint between adjacent pipe sections, thereby to restrict the folding and unfolding action of said line to cause substantially vertical movement of the open end of the line. 40

5. A liquid storage apparatus comprising a tank and a floating roof therein, a vertically foldable swivel-jointed zig-zag pipe line in the tank having an end opening into the tank and attached to the floating roof, said pipe line comprising an even number of rigid pipe sections of equal length interconnected by swivel joints and connected to a fixed pipe line leading from the tank by a swivel joint, a rigid link for each pipe section, the links being connected end to end by pivot joints, one terminal link being one half the length of the remaining links and having its projecting end pivoted to the mid-point of one terminal pipe section, the remaining links being of the length of the pipe sections and pivoted at their mid-points respectively to the remaining pipe sections at their midpoints, the projecting end of the other terminal link being mounted for restricted horizontal movement by a track member.

6. Apparatus as defined by claim 5 in which a holding means is provided for retaining the open end of said line in a substantially fixed position with respect to a point on said floating roof and in which said holding means includes a pivoted connection.
